(57) **CLAIM**

The ornamental design for a multi-function glove, as shown and described.

DESCRIPTION

FIG. 1 is a front elevational view of a multi-function glove showing my new design. The glove includes a VELCRO™ attached inner flap shown in an open position, a writing implement inserted into a zippered pouch and a wrist strap, FIG. 2 is a rear elevational view thereof shown with the inner flap and an outer flap in an open position, and with the writing implement partly inserted into the zippered pouch,

FIG. 3 is a front elevational view thereof shown with the outer flap attached to the inner flap and the pencil partly inserted into the zippered pouch;

FIG. 4 is a front elevational view thereof shown with the outer flap detached from the inner flap;

FIG. 5 is a left side elevation view thereof, shown with the outer flap attached to the inner flap and with the pencil inserted into the zippered pouch;

FIG. 6 is a right side elevational view thereof;

FIG. 7 is a top plan view thereof;

FIG. 8 is a bottom plan view thereof; and,

FIG. 9 is an orthographic view thereof shown with the writing implement removed from the zippered pouch and held in a hand.

The human hands shown in broken lines in FIG. 9 illustrate the environment in which the design is used, assist in showing how the glove appears when worn, and form no part of the claimed design. The broken line shown on the glove itself is a line of stitching and is part of the claimed design.
